UNITED STATES PATENT OFFICE

169,475

STOCKING

Lonnie Eugene Frye, Hillsdale, Va., assignor to Carroll Hosiery Corporation, New York, N. Y., a corporation of New York

Application July 9, 1952, Serial No. 20,530

Term of patent 3½ years

(Cl. D47—7)

To all whom it may concern:

Be it known that I, Lonnie Eugene Frye, a citizen of the United States and a resident of Hillsdale, county of Carroll, State of Virginia, have invented a new, original, and ornamental Design for a Stocking, of which the following is a specification, reference being had to the accompanying drawing forming part thereof.

In the drawing,

I claim:

The ornamental design for a stocking, as shown.

LONNIE EUGENE FRYE.
